**LIQUID ANHYDROUS STANNOUS SOAP
 COMPOSITIONS**

 Delaware

No Drawing. Filed Feb. 27, 1962, Ser. No. 176,112
 20 Claims. (Cl. 252—431)

This invention relates to novel metal soap compositions and to a method for making the same. More specifically, it relates to metal soap compositions with novel physical characteristics and a method for preparing them.

As is well known to those skilled in the art, soaps of heavy metals, typified by tin, may be made by a number of processes. Those processes which have been most widely used are the fusion process, and the double decomposition process.

The fusion or neutralization process involves the reaction of a compound of a metal, typically the oxide or hydroxide, with an acid to give the desired soap. Typical of such a reaction would be the formation of stannous oleate:

The double decomposition process involves the reaction of a salt of the desired metal ion with a soap of a different metal ion:

Whatever process is used, it will be highly desirable to eliminate substantially all of the water contained in the metal soap product. This water may be present as a reaction product, as in reaction (1), or as an impurity contained in the reactants. The necessity for removing substantially all the water present in the product metal soap may be explained by a consideration of reaction (1), a reversible reaction. According to this reaction, water may react with the product metal soap to give the metal oxide or hydroxide and the corresponding acid of the soap anion. The reduction of the metal soap content of the product will be found to lower the effectiveness of the soap composition in the use for which it was made.

For these reasons, it is highly desirable to produce metal soaps which are substantially anhydrous, that is soaps which contain less than about 0.5% water. These anhydrous metal soaps, typically about 99.5% anhydrous, are characterized by certain physical characteristics. Most of them are waxy solids. Others may be heavy pastes or viscous, oily, relatively immobile syrups. Metal soaps characterized by these physical forms may be difficult to handle, measure, blend, etc. In order to overcome these difficulties, it has been common to add a diluent to the metal soap product. Such diluents, e.g. mineral spirits, have necessarily been employed at high levels of concentration, thereby yielding a composition with a considerably reduced percentage of active metal soap and, consequently, reduced effectiveness in the desired use. Accordingly, it has not heretofore been possible to prepare liquid metal soap compositions which are both easily handled and contain a high percentage of active metal soap.

It is an object of this invention to provide a method for preparing liquid soap compositions. It is a further object of this invention to provide novel liquid soap compositions containing a high percentage of active metal soap.

In accordance with certain of its aspects, the process of this invention may comprise adding to a substantially anhydrous soap selected from the group consisting of

2

stannous oleate, stannous linoleate, stannous linolenate, and mixtures thereof, a liquifying amount of a compound

wherein R is a hydrocarbon radical selected from the group consisting of alkyl, aryl, aralkyl, alkenyl, cycloalkyl and cycloalkenyl radicals and polyvalent radicals derived therefrom; a and b are small integers and a+b is at least one; and R' and R'' are selected from the group consisting of alkyl, aryl, alkaryl, aralkyl, alkenyl, cycloalkyl, cycloalkenyl and hydrogen.

15 The metal soaps which may be liquified by the process of this invention may commonly be substantially anhydrous metal soaps having anions which are derived from high molecular weight ethylenically unsaturated hydrocarbon acids. Typically, these metal soaps may be made by the reaction of metal oxide with acid according to the fusion process, or by the reaction of a salt of the acid with a salt of the metal according to the double decomposition process. Although the metal soap prepared in this manner may be commonly designated as e.g. stannous oleate, it may contain a substantial proportion of compositions similar to this material.

20 The illustrative soaps which may be liquified by the process of this invention may be those wherein the anion may be derived from an ethylenically unsaturated hydrocarbon acid such as oleic acid, linoleic acid, linolenic acid, etc. Typical of the preferred soaps which may be liquified may be noted those commonly designated as stannous oleate, stannous linoleate, and stannous linolenate.

25 30 35 It is a particular feature of the liquifying technique of this invention that it may be particularly effective when used in connection with soaps which are substantially anhydrous. These substantially anhydrous soaps may be characterized by the presence of water in amount sufficiently small to minimize or substantially eliminate any appreciable degree of hydrolysis under normal handling conditions. Typically a soap may be considered substantially anhydrous when it contains less than about 0.5% by weight of water, and such soaps commonly may be either waxy solids, or heavy pastes, or viscous, oily, relatively immobile syrups.

40 45 The liquifying compounds or liquifiers contemplated in the practice of this invention are compounds of the formula

50 55 60 where R may be an alkyl radical including branched alkyls, an aryl radical, an aralkyl radical, an alkenyl radical, a cycloalkyl radical, a cycloalkenyl radical or a polyvalent radical derived therefrom, etc. and a and b are small integers whose sum is at least one. The substituent R may be an alkyl radical; typical radicals may include methyl, ethyl, propyl, i-propyl, butyl, i-butyl, sec-butyl, t-butyl, amyl, hexyl heptyl, octyl nonyl decyl, etc. ethylene (—CH₂CH₂—), propylene (—C₃H₆—), butylene (—C₄H₈—), trimethylene, etc. propane tri-yl (i.e.

65 70 75 a trivalent radical derived from propane e.g. 1,2,3-propane tri-yl) etc. Typical aryl radicals may include phenyl, naphthyl, etc. Typical aralkyl radicals may include benzyl, cinnamyl, w-phenyl butyl, etc. Typical alkenyl radicals may include allyl, butenyl, pentenyl, etc. Typical cycloalkyl radicals may include cyclohexyl, cyclopentyl, etc. Typical cycloalkenyl radicals may include cyclohexenyl, etc.

In certain aspects of this invention, b will be 0 and a will be a small integer, say 1-6, and the compound

5

will be $R(OH)_a$, i.e. an alcohol, a phenol, a glycol, a polyol, etc. For example, $R(OH)_a$ may be ethanol, isopropanol, n-butanol, n-octanol, t-butanol, n-propanol, allyl alcohol, benzyl alcohol, cyclohexanol, cyclohexenol, phenol, resorcinol, hydroquinone, ethylene glycol, propylene glycol, glycerine, sorbitol, mannitol, lauryl alcohol, stearyl alcohol, etc. Preferably, when b is 0, R will be an alkyl radical and a will be 1, 2, or 3. Preferably, the liquifier $R(OH)_a$ will be an aliphatic alcohol, e.g. ethanol, butanol; an aliphatic glycol, e.g. ethylene glycol, propylene glycol; or an aliphatic triol, e.g. glycerine.

In accordance with certain other aspects of this invention a may be 0 and b will be a small integer, say 1-6, and the compound

will be

i.e. an amine including primary, secondary, and tertiary amines, a diamine, a polyamine, etc. The substituent radicals R' and R'' may typically be hydrogen, alkyl, aryl, aralkyl, alkaryl, alkenyl, cycloalkenyl, and cycloalkyl. R' may be same as or different from R'' , and either may be the same as or different from R . R' and R'' may typically be alkyl, e.g. methyl, ethyl, propyl, i-propyl, butyl, i-butyl, sec-butyl, t-butyl, amyl, hexyl, heptyl, octyl, nonyl, decyl, etc. R' and R'' may typically be aryl, e.g. phenyl, naphthyl, etc. R' and R'' may typically be aralkyl, e.g. benzyl, cinnamyl, w-phenyl butyl, etc. R' and R'' may typically be alkenyl, e.g. allyl, buten-yl, penten-yl, etc.; or cycloalkenyl e.g. cyclohexenyl, etc.; or cycloalkyl e.g. cyclohexyl, cyclopentyl, etc.; or alkaryl, e.g. tolyl, xylyl, etc.

It will be understood that the R , R' and R'' substituents may be polyvalent, e.g. divalent and may, by joining with each other or with nitrogen atoms form cyclic structures, e.g. N-ethyl morpholine, triethylene diamine, pyrrole, pyrrolidine, etc.

When both R' and R'' radicals are hydrogen, the compound

will be a primary amine, e.g. ethylamine, aniline, n-dodecyl amine, isopropylamine, allylamine, ethylene diamine, n-butylamine, amylamine, cyclohexylamine, cyclohexenylamine, etc.

When R' is hydrogen, and R'' is a hydrocarbon radical,

60

will be a secondary amine, e.g. diethylamine, propylethylamine, N-methylaniline, diphenylamine, N,N'-dimethyl-ethylenediamine, diisopropylamine, di-n-butylamine, etc.

When both of the R' and R'' are hydrocarbon radicals,

will be a tertiary amine, e.g. triethylamine, N,N-dimethyl-aniline tri-n-butylamine, triisopropylamine, diethylpropyl-amine, ethylpropylbutylamine, etc.

Preferably when a is 0, R will be an alkyl radical, R' and R'' will be hydrogen or alkyl radicals, and

will be a primary, secondary, or tertiary aliphatic amine.

When neither a nor b is 0,

10 may contain both hydroxyl and amine radicals in the same molecule, e.g. ethanol amine, diethanolamine, 4-amino-butanol, 4-hydroxyaniline, triethanolamine, etc.

15 Liquifying amounts of the compound

20 may vary for each of the particular compounds. Typically, it may be 0.5%-3.0% preferably 0.5%-2.0% by weight of the metal soap. Lesser amounts, down to e.g. 0.1%, may be employed but liquification may not thereby be attained as satisfactorily. Increased amounts of liquifiers may be employed if desired.

25 The liquifying compound may be incorporated into the metal soap composition by any procedure which will insure complete physical mixing, so that a homogeneous mixture is formed. It may be found that the liquifying compound may be added to the metal soap while it is in the solid state and that the soap will immediately begin to liquify, so that a homogeneous liquid composition may be obtained with relatively low-shear agitation. Shaking or tumbling may also be employed to facilitate the dispersion of the liquifier throughout the metal soap. When it is desired to obtain a liquid metal soap composition in a shorter period of time, high speed or high-shear agitation may be employed, or the solid metal soap may be heated until it becomes liquid, commonly to 35-50° C. and the liquifying compound may then be rapidly dispersed therein. It will be found that the metal soap will then remain in a liquid state when cooled to room temperature; metal soaps so liquified may remain liquid for an indefinitely long period of time. It is an outstanding feature of this invention that the liquifying compound may be added to and dispersed in the reaction mixture employed in the preparation of the metal soap. When this embodiment is practiced, the substantially anhydrous metal soap product may be obtained as a liquid, and the problems of handling and blending which are associated with solid metal soaps will thereby be completely avoided.

30 Thus the novel liquid metal soap compositions of this invention may consist essentially of a substantially anhydrous metal soap selected from the group consisting of stannous oleate, stannous linoleate, stannous linolenate and mixtures thereof; a liquifying amount of a compound

35 wherein R is a hydrocarbon radical selected from the group consisting of the alkyl, aryl, aralkyl, alkenyl, cycloalkyl, and cycloalkenyl radicals; a and b are small integers and $a+b$ is at least one; and R' and R'' are selected from the group consisting of alkyl, aryl, alkaryl, aralkyl, cycloalkyl, cycloalkenyl, alkenyl, and hydrogen.

40 Illustrative liquid metal soap compositions prepared in accordance with this invention may include:

- a. Stannous oleate containing 2% ethylene glycol;
- b. Stannous oleate containing 2% glycerine;
- c. Stannous oleate containing 1% ethylene diamine;
- d. Stannous linoleate containing 1% ethylene glycol;
- e. Stannous linolenate containing 2% ethanol.

75

Practice of this invention may be further observed from inspection of the following examples.

In Examples 1-12, the noted liquifier was added to substantially anhydrous stannous oleate of high purity, having an analysis of 16.74% Sn^{+2} and 17.88% total tin, and a water content of less than 0.5%. The liquifier and the metal soap were thoroughly mixed by hand. The liquefaction temperature of each mixture was then determined by cooling the mass until it became solid and slowly raising its temperature until it was completely liquid, i.e. free of solid material. The latter temperature was recorded as the liquefaction temperature. A liquefaction temperature below room temperature i.e. about 20° C. may be satisfactory.

Example	Liquifier	Percent Liquifier	Physical State
5 17	None	0	Solid.
18	Aniline	1	Completely liq.
19	Ethanol	1	Do.
20	Glycerine	1	Do.
21	Phenol	1	Do.
22	Sorbitol	1	Do.
23	t-Butanol	1	Do.
24	Isopropanol	1	Do.
25	n-Butanol	1	Do.
26	Benzyl alcohol	1	Do.
27	Ethylene diamine	1	Do.
28	n-Propanol	1	Do.
29	Ethylene glycol	1	Do.
30	Propylene glycol	1	Do.
31	Triethylenediamine	3	Do.
15 32	N-ethyl morpholine	3	Do.

Example	Liquifier	Percent Liquifier	Liquefaction Temperature, °C.
1.	None	0	32
2.	Ethylene glycol	1	1
3.	do	2	-3
4.	Triethylenediamine	1	10
5.	do	2	13
6.	Propylene glycol	1	6
7.	do	2	10
8.	Diethylenetriamine	1	9
9.	do	2	8
10.	1-n-octanol	1	11
11.	do	2	11
12.	do	3	3

An inspection of the data of Examples 1-12 reveals the unexpected ability of the compounds

to liquefy substantially anhydrous metal soaps. It may be seen that even very small concentrations of the liquifying compound are effective in preventing solidification of the metal soap even at temperatures considerably lower than would commonly be found in areas where the metal soaps are employed. Ethylene glycol is especially effective as the liquifying agent. In fact, when ethylene glycol is used, it may be possible to prevent undesirable solidification of the metal soaps at temperatures below the freezing point of water.

In Examples 13-16 the procedure of Examples 1-12 was followed except that the sample of stannous oleate metal soap employed had an analysis of 16.4% Sn^{+2} and 17.14% total tin.

Example	Liquifier	Percent Liquifier	Liquefaction Temperature, °C.
13.	None	0	45
14.	Ethylene diamine	1	9
15.	do	2	7
16.	Ethylene glycol	2	8

In Examples 17-32 the metal soap was blended with 1 or 3 percent of the noted liquifier, and the mixtures were maintained at 20° C. for 48 hours, after which each sample was visually examined for solid particles. Samples which contained no solid metal soap particles were designated as completely liquid.

The metal soap employed was substantially anhydrous stannous oleate which was similar in composition to the soap employed in Examples 1-12 and had a liquefaction temperature of about 35° C.

When substantially anhydrous stannous linoleate or stannous linolenate is substituted for the stannous oleate of Examples 17-32, the same results may be observed.

Similar results may be obtained by using as the liquifier piperidine, ethyl amine, cyclohexanol, and cyclohexyl amine.

The novel liquid soap compositions of this invention may be especially useful in areas wherein small quantities of metal soap must be measured and handled. Typical of such an area is the use of the metal soap as a catalyst, e.g. in the formation of polyurethane foams. Similarly, they may be used in other areas wherein prior art soap compositions have been employed.

Although this invention has been illustrated by reference to certain specific examples, many modifications thereof will be apparent to one skilled in the art which fall within the scope of the invention.

We claim:

1. The process for liquifying substantially anhydrous metal soaps which comprises adding to 100 parts by weight of a soap selected from the group consisting of stannous oleate, stannous linoleate, stannous linolenate, and mixtures thereof from 0.1-3.0 parts by weight of a compound

wherein R is a hydrocarbon radical selected from the group consisting of alkyl, cycloalkyl, aryl, aralkyl, alkenyl, cycloalkenyl radicals and polyvalent radicals derived therefrom; a and b are integers from 0 to 6 and a+b is at least one; and R' and R'' are selected from the group consisting of alkyl, aryl, aralkyl, alkaryl, alkenyl, cycloalkenyl, cycloalkyl and hydrogen radicals.

2. The process for liquifying substantially anhydrous metal soaps as claimed in claim 1 wherein b is 0 and the compound is $R(OH)_a$.

3. The process for liquifying substantially anhydrous metal soaps as claimed in claim 1 wherein a is 0 and the compound is

4. The process for liquifying substantially anhydrous metal soaps as claimed in claim 1 wherein the compound

is present in the amount of at least 0.5 part by weight per 100 parts by weight of metal soap.

5. The process for liquifying substantially anhydrous metal soaps as claimed in claim 1 wherein the metal soap is stannous oleate.

6. The process for liquifying substantially anhydrous metal soaps as claimed in claim 1 wherein

is ethylene glycol.

7. The process for liquifying substantially anhydrous metal soaps as claimed in claim 1 wherein

is glycerine.

8. The process for liquifying substantially anhydrous metal soaps as claimed in claim 1 wherein the compound

is present in the amount of about 0.5-3.0 parts by weight per 100 parts by weight of metal soap.

9. The process for liquifying substantially anhydrous stannous oleate which comprises adding to 100 parts by weight of said stannous oleate about 0.5-3.0 parts by weight of a compound

wherein R is a hydrocarbon radical selected from the group consisting of alkyl, cycloalkyl, aryl, aralkyl, alkenyl, cycloalkenyl radicals and polyvalent radicals derived therefrom; a and b are integers from 0 to 6 and a+b is at least one; and R' and R'' are selected from the group consisting of alkyl, aryl, aralkyl, alkaryl, alkenyl, cycloalkenyl, cycloalkyl and hydrogen radicals.

10. A novel liquid metal soap composition consisting essentially of substantially anhydrous metal soap selected from the group consisting of stannous oleate, stannous linoleate, stannous linolenate, and mixtures thereof; and from 0.1-3.0 parts by weight per 100 parts by weight of said metal soap of a compound

wherein R is a hydrocarbon radical selected from the group consisting of the alkyl, aryl, aralkyl, alkenyl, cycloalkyl, and cycloalkenyl radicals and polyvalent radicals derived therefrom; a and b are integers from 0 to 6 and a+b is at least one; and R' and R'' are selected from the group consisting of alkyl, aryl, aralkyl, alkaryl, alkenyl, cycloalkenyl, cycloalkyl and hydrogen radicals.

11. A novel liquid metal soap composition as claimed in claim 10 wherein b is 0.

12. A novel liquid metal soap composition as claimed in claim 10 wherein a is 0.

13. A novel liquid metal soap composition as claimed in claim 10 wherein the compound

is present in the amount of at least 0.5 part by weight per 100 parts by weight of metal soap.

14. A novel liquid metal soap composition as claimed in claim 10 wherein the metal soap is stannous oleate.

15. A novel liquid metal soap composition as claimed in claim 10 wherein

is ethylene glycol.

16. A novel liquid metal soap composition as claimed in claim 10 wherein

is glycerine.

17. A novel liquid metal soap composition as claimed in claim 10 wherein the compound

is present in the amount of about 0.5-3 parts by weight per 100 parts by weight of metal soap.

18. A novel liquid metal soap composition consisting essentially of 100 parts by weight of substantially anhydrous stannous oleate and about 0.5-2.0 parts by weight of a compound

wherein R is a hydrocarbon radical selected from the group consisting of the alkyl, aryl, aralkyl, alkenyl, cycloalkyl, and cycloalkenyl radicals and polyvalent radicals derived therefrom; a and b are integers from 0 to 6 and a+b is at least one; and R' and R'' are selected from the group consisting of alkyl, aryl, aralkyl, alkaryl, alkenyl, cycloalkenyl, cycloalkyl and hydrogen radicals.

19. A novel liquid metal soap composition consisting essentially of 100 parts of stannous oleate and about 0.5-2.0 parts of ethylene glycol.

20. A novel liquid metal soap composition consisting essentially of 100 parts of stannous oleate and about 0.5-2.0 parts of glycerine.
